UNITED STATES PATENT OFFICE.

CLARENCE HENRY HAAS AND LEWIS JOHN MITCHELL, OF WARREN, OHIO.

STEAM BOILER.

Application filed February 19, 1926. Serial No. 89,452.

This invention relates to steam boilers of the upright single tube type such as is employed in the generation of steam for pressing machines, etc. etc.

5 The primary object of the invention resides in the provision of such a boiler that is so constructed as to take advantage of the entire heat unit and to secure substantially ninety-five per cent combustion in the fire 10 box and flue, thus eliminating fire hazards of over-heated stacks and danger to lives by carbon monoxide gas fumes.

To the attainment of this end, there is arranged within the flue of the boiler a 15 plurality of predetermined spaced deflectors that serve to throw the heat units and products of combustion against the wall of the flue resulting in said complete combustion of the gases and the utilization of the entire 20 heat unit in directing the same upon said wall.

The invention further aims to provide a construction wherein the steam will be generated within a relatively short while 25 through reason of the fact that the water throughout the entire length of the boiler is heated by the action of the heat unit passing through said flue which is arranged throughout the length of the boiler.

30 A still further object resides in the provision of a series of deflectors within said flue in order that there will be no waste of the heat unit that in types of boilers now upon the market pass directly through the 35 center of the flue from the bottom of the boiler out through the smoke stack, in the present instance all of the heat units necessarily contacting the wall of the flue.

Other objects will appear as the nature of 40 the invention will be better understood, the same comprising the novel form, combination, and arrangement of parts, hereinafter more fully described, shown in the accompanying drawing, and claimed.

45 In the drawing:—

The figure is a detail longitudinal section of a steam boiler constructed in accordance with the present invention.

Now having particular reference to the 50 drawing our novel boiler constitutes the provision of an open ended cylindrical shell 5 of desired capacity that is provided at its upper open end with a conventional form of head 6 within which is an enlarged central opening 7.

Within the shell 5 at the lower end thereof

is an interior shell 8 functioning as the fire box for the boiler. This shell is also of cylindrical formation being open at its opposite ends and is of slightly less diameter 60 than the diameter of the outer shell 5 for providing a water space therebetween. The lower end of this interior shell 8 is flared outwardly at 9 that serves as the bottom wall of the boiler, while dependent therefrom is a plane skirt 10 that closely engages the interior of the shell 5 and is riveted or otherwise suitably secured thereto as at 11.

The upper open end of the interior shell 8 is provided with a conventional head 12 70 that is also formed with a central circular opening 13 in registration with the opening 7 of the head 6, and within which is arranged one end of a relatively wide cylindrical flue pipe 14, the other end thereof 75 being arranged in said opening of the head 6.

Extending through the flue 14 and shell 8 providing the fire box for the boiler and arranged within the center thereof is a rod 15, 80 the upper end of which is threaded for connection to a cross bar 16 that rests upon the upper end of the flue 14 which projects through the opening 7 in the boiler head 6. Arranged in predetermined spaced relation 85 upon this rod 15 within the flue pipe 14 are conical deflector plates 17 of such a cross sectional area that the flared edge thereof will be in slight spaced relation with the interior of the flue pipe causing the heat units 90 and products of combustion to be deflected against said flue pipe for thus utilizing the entire heat unit in the production of steam and also causing a combustion of the gases which would otherwise escape through the 95 flue by non-contact with the heated wall thereof.

Similarly arranged upon the rod 15 within the shell 8 forming the fire box for the boiler is a pair of relatively larger deflectors 100 18—18, the upper one of which is inverted as clearly shown in the drawings. The flared ends of these deflectors also being in slight spaced relation with the interior of the fire box for purposes similar to those of the deflectors 17—17.

It will thus be seen that we have provided a highly novel, simple, and efficient form of steam boiler wherein steam will be quickly generated by reason of the fact that all of 110 these units are projected against the interior of the fire box and flue which is arranged

within the boiler and wherein the complete combustion of the gases will be brought about, thus eliminating the collection of soot and impurities in the fire box and flue which will also eliminate the collection of rust and scale around the outside of the fire box and flue or in the water and steam compartment.

Leading into and from the shell 5 are the usual inlet and discharge pipes 19 and 20 respectively, and even though we have herein shown and described the most practical embodiment of the present invention it is nevertheless to be understood that minor changes may be made therein without departing from the spirit and scope of the appended claims.

Having thus described the invention, what we claim as new and desire to secure by Letters Patent is:—

1. A vertical single flue boiler having an

annular steam and water chamber surrounding said flue and coextensive therewith, the base portion of said chamber being of restricted width from inner to outer wall, and a baffle disposed in said flue, said baffle including a deflecting member in the form of an imperforate cone-shaped plate with its apex uppermost, said member located adjacent the flue inlet and being of a diameter approximating that of the flue.

2. A boiler as defined in claim 1 in which said baffle includes additional spaced similarly-shaped deflecting members, the lowermost of said additional members being disposed with its apex downward.

In testimony whereof we affix our signatures.

CLARENCE HENRY HAAS.
LEWIS JOHN MITCHELL.
